(57) **CLAIM**

The ornamental design for a tube cutter, as shown and described.

DESCRIPTION

FIG. 1 is a front-right-top perspective view of a tube cutter in accordance with the present invention;

FIG. 2 is a front-left-top perspective view thereof;

FIG. 3 is a rear-right-top perspective view thereof;

FIG. 4 is a rear-left-top perspective view thereof;

FIG. 5 is a front view of FIG. 1; and,

FIG. 6 is a rear view of FIG. 1.

The broken lines in the drawings are for the purpose of illustrating portions of the tube cutter that form no part of the claimed design.
